UNITED STATES PATENT OFFICE.

PETER COPLAND, OF JOHNSTOWN, OHIO, ASSIGNOR OF ONE-HALF HIS
RIGHT TO JAMES W. WOLFE, OF SAME PLACE.

IMPROVEMENT IN CARRIAGE-TOPS.

Specification forming part of Letters Patent No. **195,986**, dated October 9, 1877; application filed
September 19, 1877.

To all whom it may concern:

Be it known that I, PETER COPLAND, of Johnstown, county of Licking, and State of Ohio, have invented certain new and useful Improvements in Carriage-Tops; and I do hereby declare the following to be a full, clear, and exact description thereof, reference being had to the annexed drawing, in which—

Figure 1 is a side view of my improved carriage-top. Fig. 2 is a similar view thereof when let down; and Fig. 3 is a detached sectional view.

Corresponding parts in the several figures are denoted by like letters.

This invention relates to certain improvements in carriage-tops, and has particular reference to that class having a rigid canopy or top; and it consists, principally, in the manner of putting the parts together, and their relative arrangement and combination, substantially as hereinafter more fully set forth and claimed.

In the annexed drawing, A refers to the seat, the back-rail B of which is provided with arms b b, having lateral or right angular projections b¹ b², which serve as pivots for the lower ends of the vertical bows of the canopy or top, and the lower ends of the jointed braces, to be hereinafter more fully referred to. B¹ refers to a horizontal frame, which may be made of a continuous piece, or of two bows spliced together and fastened. B² is a bow, centrally disposed in the frame B¹, and having its arms or depending portions connected to the back-rail of the seat, as above stated, and standing perpendicularly, to be out of the way of the person getting in and out of the vehicle. The bow B² and frame B¹ are mortised, so as to permit of their being halved together and secured or fastened in place by rivets or bolts c upon the inner or rear sides of the irons or plates c¹ c¹, having the projections c² c² serving as pivots for the jointed braces D D. To prevent the plates c¹ c¹, turning they are perforated, and screws or other fastenings passed through

said perforations, and inserted into the frame B¹, securing said plates in position. By having the plates c¹ c¹ and the rivets or bolts c constructed in connection with the pivots c² c² of the jointed braces D D, the frame B¹ and bow B² of the top or canopy are simultaneously put together, and fastened in place with providing pivots for the upper ends of the braces D D. The plates c¹ c¹ also serve to brace and strengthen the mortised or weakened points of the frame and bow B².

Two other bows, E E, of less curvature, and smaller than the bow B², suitably arranged upon each side of the latter, and fastened to the frame B¹, assist in forming the top, which are covered in the usual manner and with the usual material and trimmings to complete the top or canopy. The top or canopy, when down, is supported in place upon the lower pivots b² of the jointed braces D D.

It will also be noticed that the canopy or top can be lowered to such a point as to clear any obstruction under which the horse can pass. When in a lowered position the top or canopy will rest at a point between and in front of the hind wheels of the vehicle to lessen the liability of mud, &c., being thrown thereon by the wheels.

Having thus described my invention, what I claim, and desire to secure by Letters Patent, is—

The combination of the frame B¹, bow B², the two being mortised together, plates c¹ c¹ having rivets or bolts c fastening the said bow and frame together, and projections or pivots c² c², and the jointed braces D D, substantially as and for the purposes set forth.

In testimony whereof I have hereunto signed my name in presence of two subscribing witnesses.

PETER COPLAND. [L. S.]
